UNITED STATES PATENT OFFICE.

FREDERICK A. WEGNER, OF BUFFALO, NEW YORK.

GRAIN-SEPARATOR.

1,280,600.

Specification of Letters Patent.

Patented Oct. 1, 1918.

Application filed May 21, 1915. Serial No. 29,687.

To all whom it may concern:

Be it known that I, FREDERICK A. WEGNER, a citizen of the United States, residing at Buffalo, in the county of Erie and State 5 of New York, have invented certain new and useful Improvements in Grain-Separators, of which the following is a specification, reference being had therein to the accompanying drawing.

10 This invention relates to grain separators, and has reference more particularly to such separators wherein air currents are directed upwardly through the mass of grain to materially assist in its separation.

15 It is well known that grain of various kinds, such for instance as wheat and oats, differs in size and specific gravity, and I have taken advantage of these known facts in devising an apparatus whereby the lighter 20 grain may be separated in an effective manner from the grain of relatively greater specific gravity.

In the usual type of fanning separator the air is delivered by the fan in undivided currents and it is a well known fact that under these conditions most of the air is directed at a point near the central portion of the screens or other supporting surfaces for the grain and a comparatively small amount of 30 the air is delivered at the sides thereof, so that a large part of the material being separated derives but little benefit from the resultant effect of the air blasts or currents.

It is, therefore, the primary object of this 35 invention to provide means whereby the air delivered below the separating screens and directed upwardly through the mass of material to be separated, may be controlled to bring about an even and effective distribution of the air beneath the entire screen surfaces; or as may be more broadly stated, to bring about this even distribution of air regardless of the manner in which the air 40 is delivered to the material being treated.

45 A further object of the invention is the provision of a plurality of air regulating devices, each independently controlled for the purpose of varying the air supply at any desired point within the apparatus, thus 50 allowing for the control of air to suit various conditions.

The invention can be embodied in different forms, some of which are illustrated, and to the accomplishment of the foregoing 55 and such other objects as may hereinafter appear, the invention consists in the features

and combination of parts hereinafter more particularly described and claimed, reference being had to the accompanying drawings, wherein—

60

Figure 1 is a vertical sectional view of the apparatus embodying my invention;

65

Fig. 2 is an end elevation thereof, partly in section, said section being taken on the line 2—2 of Fig. 1;

65

Fig. 3 is a detail view of the fan;

70

Fig. 4 is a vertical sectional view of the separator embodying certain modifications of the air regulating means, and the grain supporting surfaces;

70

Fig. 5 is a vertical sectional view of the separator shown in Fig. 4, said section being taken on line 5—5 of said figure;

75

Fig. 6 is a detail sectional view of a modified form of certain of the grain supporting surfaces, said supporting surfaces being capable of adjustment to change their inclination, and the partitions carried by said supporting surfaces being made extensible to allow for said adjustment.

80

Fig. 7 is a detail perspective view of one of the grain supporting surfaces and its extensible partitions, and

85

Fig. 8 is a detail perspective view of the grain discharge chutes shown in Fig. 6.

85

Referring to the drawings, 1 denotes a suitable frame upon which the various parts of the separator are supported, the same containing in the present instance a shaking shoe 2, suspended by means of spring metal straps 3 from the side frames of the supporting structure. This shoe is provided with the desired number of inclined sieves or screens 4, as usual, and the shoe carrying such screens is adapted to be reciprocated or shaken by any suitable means such for instance as the eccentrics 5 mounted on an eccentric shaft 6, journaled upon one of the side frames, actuating arms 7 being provided for connecting the eccentrics with the 90 side of the shoe.

90

The material to be separated is fed to the screens from a hopper 8 by means of the feed roller 9, the grain being first delivered to an inclined perforated table 10, the purpose of which is to separate from the grain, such as wheat and oats, any foreign matter which might be contained therein, such foreign matter being carried by gravity to the lower edge of the inclined table and discharged into a chute 11, in the usual way. The grain passes through the perforations in 100

95

100

105

105

110

the inclined table 10 and is delivered to the separating shoe 2, where such grain is separated in a manner to be hereinafter more fully set forth.

5 The grain delivered to the shoe is agitated due to the shaking motion imparted to said shoe, and also from the fact that air currents are directed upwardly through the mass of material supported by the screens 10 carried by the shoe, a suitable fan 12 being used for supplying the air for this purpose. Due to this agitation of the material the lighter grain, such for instance as oats, is lifted to the top of the mass supported by 15 each shaking screen, while the heavier grain will gravitate to the bottom, thus stratifying the mass of material and allowing the wheat or heavier and smaller grain, and any of the lighter grain which might be carried along 20 with the wheat, to pass through the meshes of the screen to the next screen below, where such material is subjected to a further and like treatment. After such successive treatment of the grain upon the series of shaking 25 screens the wheat or heavier grain is finally conveyed to a chute 13, from where the same is delivered to a suitable bin or other receptacle. The oats or lighter material is carried over the lower end of each shaking 30 screen and delivered finally into a chute 14 which discharges said material into any suitable storage bin.

Heretofore in the separation of grain wherein air has been directed through the 35 mass of material to assist in the separation, no effective means has been provided for the control of this air. In the present instance perfect control of air is provided for, and furthermore, the regulating devices to be 40 hereinafter more fully set forth, may be so operated as to permit the proper amount of air to be directed over and through the entire mass of material supported by the shaking screens. To accomplish this end the fan 45 casing 15 is suitably extended in an upward direction to cover or suitably inclose the rear end of the shaking shoe, forming an air trunk 16 for directing the air between the series of shaking screens. Suitable valves or 50 other air regulating devices are provided, as indicated at 17, for controlling the amount of air to be delivered to each screen. The valves are capable of independent adjustment in any preferred manner, so that the 55 amount of air directed between two adjacent screens may be varied as desired to suit conditions.

Furthermore, a plurality of tubular arms 18, preferably of the cross section shown in 60 Fig. 2, extend in a horizontal direction from the fan casing and are arranged beneath the shaking shoe, the arms being of a length substantially that of the shoe, and a sufficient number of said arms being provided to 65 extend across the entire width of said shoe.

The tubular arms are perforated along their sides, as indicated at 19, through which perforations air may be directed in an upward direction through the mass of material being separated. An angular valve plate 20 is 70 adapted to coöperate with each tubular arm, said valve plate having perforations 21, similar to the perforations 19, in the arms, and adapted to register therewith in certain positions of the valve plate. Each one of the valve plates is independently operated, and as will be obvious the amount of air to be delivered by each tubular arm may be varied by adjusting the valve plates to change the effective size of the air discharge perforations in said arms. It is also to be noted that the air discharge perforations in any one arm may be entirely closed by its valve plate if conditions are such that this is necessary. 85

It has been found that with the usual and ordinary type of fan a greater amount of air is delivered to the central portion of the screen, so that the mass of material supported upon the screens at the sides thereof, 90 does not receive the proper amount of air to effect a perfect separation. By the means and devices just described, however, the air delivered by the fan can be controlled in an effective manner and an even and equal distribution of air to the entire mass of material can be provided. 95

The fan 12 is provided with relatively narrow blades 12' of a length approximately the width of the screens, and these blades have 100 centrally located cut-out portions 12'' at their outer edges, whereby a better distribution of air across the entire width of the screens or other grain supporting surfaces is maintained, than can be accomplished by a 105 fan of the ordinary or usual type.

Referring particularly to the structure shown in Figs. 4 and 5 of the drawings, it will be noted that horizontal grain supporting plates 22 are provided, serving as baffles for directing the air in a proper and efficient manner to the screens, and vertical partitions 23 are arranged between these baffle plates and the screens. In this manner a plurality of air channels beneath each 110 screen are provided and the air passing through each one of these channels is independently controlled by means of valves 24, located at the entrance to each channel, thus allowing for a complete control of the air 115 whereby an even distribution thereof beneath the screen surfaces may be effected. Vertical partitions 25 may also be provided, as indicated, so that a series of air channels are arranged below the shaking shoe, these 120 channels being similar in all respects to the channels between the screens carried by said shoe. Valves or other adjustable control devices 26 are located at the entrance to each 125 one of these channels and for a purpose as 130

above set forth in connection with the valves 24, it being noted that each set of air control devices is adapted to be independently adjusted as desired.

5 Instead of having a fan and fan casing located as illustrated in Fig. 1 of the drawings, a fan or blower may be arranged in any other desired position, and the air delivered thereby carried to the separator 10 through a suitable air trunk as indicated at 27, in Fig. 4 of the drawings.

In the modified construction shown in Figs. 6 and 7, grain supporting plates 28 are provided, said plates being pivoted at 29 to 15 the screens 4. These plates 28 are normally inclined in a downward direction from their pivotal points, so that the heavier grain supported by each plate may be directed downwardly into the horizontally arranged 20 chutes 30, one of said chutes 30 being provided for each grain supporting plate 28. The grain delivered to these chutes 30 is directed through short horizontal pipe sections 31, which discharge the grain into a 25 vertical pipe or tubular shaft 32, located at one end of said chutes. This vertical pipe may deliver the grain into any suitable bin or other receptacle. It is, of course, to be understood that in this construction as in 30 the structures heretofore described, the grain supporting plates or other surfaces are carried by the shaking shoe, so that as this shoe is reciprocated the grain supported by said inclined plates 28 is agitated thus stratifying the same, and allowing the heavier material, such as wheat, to be carried by gravity down said plates and into the chutes 30, the lighter material, such for instance as oats, being blown off or removed from the 40 plates by means of the action of air blasts or currents directed between adjacent grain supporting plates 28.

It is to be further noted in connection with the structure just described that the grain 45 supporting plates 28 being pivotally mounted, as above set forth, said plates may be adjusted to change the inclination thereof to suit conditions, and to allow for this adjustment, the vertical partitions supported 50 by the plates are made extensible. These partitions are made up of two sections 33 and 34, connected together in such a manner as to have sliding engagement one with the other in a vertical direction for varying 55 the height of said partition, a spring 35 being provided for normally maintaining said sections in extended position with the upper edge of the section 34 in direct contact with the underside of the plate 28 above it. The 60 section 33 of each partition is fixed to the plate 28 as clearly shown in Fig. 7 of the drawing, and the section 34 thereof which is slidably connected to the section 33 is adapted to adjust itself to the supporting plate 65 or surface directly above it. That is to say,

the upper edge of the section 34 will, by the construction just described, adapt itself to the inclination of the underside of the grain supporting surface with which it engages regardless of the inclination of the grain 70 supporting plate upon which the partition is mounted. It will therefore be seen that the partitions which constitute the side walls of the air channels heretofore referred to, adapt themselves to the varying space between adjacent supporting plates, and that said channels at their sides are completely closed at all times.

While I have shown and described in some detail a specific embodiment of the invention, well adapted for performing the function herein set forth, it will be apparent that many changes in details of construction might be made without departure from the spirit of my invention and within the 85 scope of the appended claims.

I claim:

1. In a grain separator, a plurality of shaking screens, means for supplying grain thereto, means for subjecting the material supported by said screens to the action of air currents, and a plurality of independently adjusted devices for controlling the air currents delivered to each screen.

2. In a grain separator, a shaking shoe 95 provided with a plurality of sieves or screens, means for causing the material supported by said screens to be subject to upwardly directed air currents, and a plurality of independently adjusted devices for controlling the air currents delivered to each screen.

3. In a grain separator, a shaking shoe 100 provided with sieves or screens, means for subjecting the material supported by said screens to the action of air currents, a series 105 of air channels between each two adjacent screens, and an independent means for controlling the air passing through each channel.

4. In a grain separator, a shaking shoe provided with sieves or screens, means for subjecting the material supported by said screens to the action of air currents, a series of air channels between each two adjacent screens, and means located at the entrance 110 of each channel for controlling the air passing therethrough.

5. In a grain separator, a shaking shoe 115 provided with sieves or screens, means for subjecting the material supported by said screens to the action of air currents, a series of air channels between each two adjacent screens, and independently operated valves for controlling the air passing through said channels.

6. In a grain separator, a shaking shoe 120 provided with sieves or screens, means for subjecting the material supported by said screens to the action of air currents, a series 125 of air channels between each two adjacent screens, and independently operated valves for controlling the air passing through said channels.

- of air channels between each two adjacent screens, and valves pivoted at the entrance to each channel and adapted to be independently adjusted for controlling the air 5 passing through said channels.
7. In a grain separator, a shaking shoe provided with sieves or screens, means for causing air to be directed upwardly through the mass of material supported by the 10 screens, a series of vertical partitions arranged beneath the shoe for dividing this space into a number of air channels, and independently operated valves for controlling the air delivered to each channel.
- 15 8. In a grain separator, a shaking shoe provided with sieves or screens, means for subjecting the material supported by said screens to the action of air currents, a series of vertical partitions arranged between each 20 two adjacent screens, and independently operated valves for controlling the air delivered to each channel.
9. In a grain separator, a shaking shoe provided with sieves or screens, means for 25 subjecting the material supported by said screens to the action of air blasts, a baffle plate arranged between each two adjacent screens for deflecting the air in an upward direction against the screens, a series of 30 vertical partitions carried by said baffle plates and dividing the space between the screens into a number of air channels, and means for independently controlling the air supplied to each channel.
- 35 10. In a grain separator, a shoe provided with sieves or screens, means for shaking said shoe in a direction at right angles to the direction of flow of material upon the sieves or screens, means for subjecting the 40 material supported by each screen to the action of air currents, and a plurality of independently adjusted devices for controlling the air currents delivered to each screen.
11. In a grain separator, a shoe provided 45 with inclined grain supporting surfaces, means for shaking said shoe in a direction at right angles to the direction of flow of the material supported by said inclined surfaces, means for subjecting the material to 50 the action of air currents, and a plurality of independently adjusted devices for controlling the air currents delivered to each supporting surface.
12. In a grain separator, a shaking shoe 55 provided with a plurality of inclined grain supporting surfaces, means for subjecting the material supported by said surfaces to the action of air currents, and a plurality
- of independently adjusted devices for controlling the air currents delivered to each supporting surface. 60
13. In a grain separator, a shaking shoe provided with a plurality of inclined grain supporting surfaces, means for adjusting the inclination of said surfaces, means for subjecting the material supported by said surfaces to the action of air currents, and a plurality of independently adjusted devices for controlling the air currents delivered to each supporting surface. 65
14. In a grain separator, a shaking shoe provided with sieves or screens, and means for subjecting the material supported by said screens to the action of air currents, said means comprising a fan having relatively narrow blades of a length substantially the width of the screens, said blades having centrally located cut-out portions at their outer edges, whereby an even distribution of air is delivered to the mass of material supported by said screens. 70
15. In a grain separator, a shaking shoe provided with inclined grain supporting surfaces, means for adjusting the inclination of said surfaces, vertically arranged 85 extensible partitions carried by said supporting surfaces, means for maintaining said partitions in extended position according to the adjustment of the supporting surfaces, and means for subjecting the material supported by said surfaces to the action of air currents. 90
16. In a grain separator, a shaking shoe provided with inclined grain supporting surfaces, means for adjusting the inclination of said surfaces, adjustable partitions carried by said supporting surfaces, and means for subjecting the material supported by said surfaces to the action of air currents. 95
17. In a grain separator, a shaking shoe provided with inclined grain supporting surfaces, means for adjusting the inclination of said surfaces, extensible partitions carried by said supporting surfaces, a spring 105 for normally holding the partitions in extended position according to the adjustment of the supporting surfaces, and means for subjecting the material supported by said surfaces to the action of air currents. 110
- In testimony whereof I affix my signature in presence of two witnesses.
